draulic Development Corporation, Inc., Wil-
mington, Del., a corporation of Delaware

Application March 6, 1939, Serial No. 83,362

Term of patent 14 years

To all whom it may concern:

Be it known that we, Harold Van Doren and George Geiger, citizens of the United States, residing at Toledo, in the county of Lucas and State of Ohio, and Mount Gilead, in the county of Morrow and State of Ohio, respectively, have invented a new, original, and ornamental Design for a Radial Pump Unit, of which the following is a specification, reference being had to the accompanying drawing forming a part thereof.

In the drawing:

Figure 1 is a front elevation of a radial pump unit showing our new design;

Figure 2 is a rear elevation thereof;

Figure 3 is a side elevation thereof; and

Figure 4 is a plan view of the pump unit.

We claim:

The ornamental design for a radial pump unit, as shown.

HAROLD VAN DOREN.
GEORGE GEIGER.
